UNITED STATES PATENT OFFICE

153,844

DESIGN FOR A BURIAL VAULT NAME PLATE

Leo Stephen Basalay, Chicago, Ill.

Application April 9, 1948, Serial No. 145,625

Term of patent 7 years

(Cl. D19—2)

To all whom it may concern:

Be it known that I, Leo S. Basalay, a citizen of the United States of America, residing at Chicago, in the county of Cook and State of Illinois, have invented a new, original, and ornamental Design for Burial Vault Name Plates, of which the following is a specification, reference being had to the accompanying drawing, forming part thereof.

In the drawing:

Fig. 1 is a face view of a burial vault name plate, showing my new design, and

Fig. 2 is an edge view of the burial vault name plate shown in Fig. 1.

I claim:

The ornamental design for a burial vault name plate, as shown.

LEO STEPHEN BASALAY.
